UNITED STATES PATENT OFFICE.

WALTER H. BARRY, OF CHICAGO, ILLINOIS.

WINDOW FRAME AND SASH.

No. 856,017.

Specification of Letters Patent.

Patented June 4, 1907.

Application filed July 16, 1906. Serial No. 326,374.

To all whom it may concern:

Be it known that I, WALTER H. BARRY, a citizen of the United States, residing at Chicago, in the county of Cook and State of Illinois, have invented certain new and useful Improvements in Window Frames and Sashes, of which the following is a specification.

My invention relates to window frames and sashes therefor and more particularly to such as are constructed entirely of metal, and its objects are; to provide a frame and sash of an exceedingly simple and durable construction which may be fitted into any ordinary opening of the proper size without special preparation; to provide a frame in which the sash can be readily fitted after the former has been secured in place and from which it can be as readily removed; to provide means for forming a tight joint between the frame and sash which will be practically weather proof and prevent rattling; to provide means for securing the glass in the sash and to provide a window frame and sash which may be constructed entirely of sections of the ordinary commercial shapes fastened together by means of bolts, rivets or in any other preferred manner. These and other objects which will hereinafter appear I attain by means of the construction illustrated in preferred form in the accompanying drawings wherein:

Figure 1 is a view in elevation of my improved window frame and sash,

Figure 2 is a vertical section of the same taken on the line II—II of Figure 1, the sash being illustrated as pivoted to the frame and in its tilted or open position,

Figure 3 is a horizontal section on an enlarged scale, taken on the line III—III of Figure 1 through the upper portion of the frame and sash,

Figure 4 is a similar view on the line IV—IV through the lower portion of the same,

Figure 5 is a detail sectional view of the pivotal connection between the frame and sash,

Figure 6 is a full view of the slot in which the pivot is fitted, and

Figure 7 is a sectional detail of one corner of the sash.

While my improved form of construction is adapted to be used in connection with window frames, and sashes of various kinds, such for instance as those in which the sashes slide as well as those having fixed sashes, I

have shown it as applied to a window in which the sash swings upon a horizontal axis, although the sash may be fitted to swing upon a vertical axis or be mounted in any other suitable manner without departing from the nature of my invention.

As illustrated in the accompanying drawings I prefer to construct the rectangular frame 8, of angle iron, as being best adapted to form a light and stiff frame as well as one which can be readily secured in the window opening, although if desired, flat strips of iron or channel bars may be used instead. The end and side pieces of the frame are mitered together at the corners or joined and held together in any other preferred manner. Around the inner face of the frame 8 are secured the retaining or weather strips 9 adapted to fit closely around the sash and prevent the same from rattling in a manner to be presently described.

The sash consists of sections of gas pipe 10 joined together at the corners by means of the elbow pieces 11, fitted therein in a manner to form a flush joint, and braced at the middle by means of a section of pipe 11^a connected to the side pieces by the T shaped pivot pieces 12 which are adapted to fit into the pipe sections and form a flush joint in a manner similar to the corner sections. The pivot pieces 12 are provided with lugs or projections 12^a which fit in slots 13 formed in the sides of the frame, and act as pivots upon which the frame swings. By reference to Figures 2, 3, and 4, it will be seen that the upper retaining pieces 9 are arranged to fit around one end of the sash while the corresponding lower pieces fit around the opposite side, such an arrangement allowing the sash to swing freely in one direction, and hold it rigidly in place when in a vertical or intermediate position.

By reference to Figures 3 and 4 it will be seen that the glass is held in position in the sash by means of two metal holding strips or members 14 placed one upon the other and having one end bent out at approximately right angles to clasp the glass on each side, and the other end curved to fit the sides of the sash 10, to which they are riveted or secured in any other suitable manner.

While I have shown the retaining pieces 9 arranged to permit of the use of a swinging sash, and in connection with the sloping slot 13 open at one end, to permit the sash to be readily removed from the frame, said pieces

could be utilized as guides for a sliding sash, or they could run continuously around one side of the sash if it is desired to fix the same permanently in the frame, or have it open on hinges, without departing from the nature or scope of my invention. Other advantages of the device will readily occur to those familiar to the art.

Having thus described my invention and illustrated its use, what I claim as new and desire to secure by Letters Patent, is the following:

1. In combination, a window frame, a swinging sash, and a retaining strip having one edge secured to the frame intermediate the sash and frame, and the other at an angle to the first edge and arranged to embrace a portion of the sash when the window is closed.
2. In combination, a window frame composed of iron of ordinary commercial shapes, a sash pivoted to swing therein, and retaining strips interposed between the frame and sash, said strips being attached to the frame and adapted to partially surround the sash, the strips on opposite sides of the pivot being reversely turned to surround opposite sides of the sash and permit it to swing open in one direction.
3. In combination, a window sash, and an independent sash retaining member secured thereto and comprising a member having a

projecting grooved portion for the reception of the glass, and a body portion at an angle to the grooved portion and fitting the sash.

4. In combination, a window sash, and a pair of holding members having their inner ends overlapping and secured to the sash, and their other ends bent at an angle and spaced apart for the reception of the glass.

5. In combination in a window sash, an outside member composed of sections of pipe, and a pair of holding members, said holding members being curved at one end to fit the outside member, and having their other ends turned out to bear on opposite sides of the glass.

6. In combination in a window sash, a pair of adjoining tubular members, a connecting member therebetween, said connecting member having reduced end portions adapted to fit the interior of the tubular sections and a middle section of the same diameter as the tubular sections, whereby a flush joint is secured.

In testimony whereof, I hereunto sign my name in the presence of the two subscribed witnesses.

WALTER H. BARRY.
